US00D649516S

(12) **United States Design Patent**
Thauer

(10) **Patent No.:** **US D649,516 S**
(45) **Date of Patent:** **** Nov. 29, 2011**

(54) **ELECTRODE LEAD FOR ELECTRICAL STIMULATOR**

(75) Inventor: **Robert Thauer**, Santa Ana, CA (US)

(73) Assignee: **VisionQuest Industries, Inc.**, Vista, CA (US)

(**) Term: **14 Years**

(21) Appl. No.: **29/133,999**

(22) Filed: **Sep. 2, 1999**

(51) **LOC (9) Cl.** **13-03**

(52) **U.S. Cl.** **D13/147**

(58) **Field of Classification Search** **D13/133, D13/146, 147, 153, 154, 156, 184, 199; D24/133, D24/155, 167, 168, 170, 186, 187, 200, 231; 439/178, 179, 180, 224, 252, 266, 374, 378, 439/380, 476.1, 894, 909; 607/115, 116, 607/117, 122**

See application file for complete search history.

(57) **CLAIM**

The ornamental design for an electrode lead for electrical stimulator, as shown and described.

DESCRIPTION

FIG. 1 is an enlarged perspective view of a portion of one end of an electrode lead for electrical stimulator, showing my new design;

FIG. 2 is a perspective view of the opposite end thereof; and, FIG. 3 is a perspective view of an electrode lead for electrical stimulator thereof.
